DESIGN FOR A CIGARETTE CASE

Charles M. Pritzker, New York, N. Y.

Application October 4, 1944, Serial No. 115,614

Term of patent 7 years

(Cl. D85—2)

To all whom it may concern:

Be it known that I, Charles M. Pritzker, a citizen of the United States and a resident of 1150 Fifth Avenue, Borough of Manhattan, in the county and State of New York, have invented a new, original, and ornamental Design for a Cigarette Case, of which the following is a specification, reference being had to the accompanying drawings forming a part thereof.

Fig. 1 is a perspective view of a cigarette case in open position showing my design;

Fig. 2 is a top view thereof in closed position;
Fig. 3 is a section through line 3—3 of Fig. 2;
Fig. 4 is a section through line 4—4 of Fig. 2;
Fig. 5 is an enlarged section through line 5—5 of Fig. 2.

I claim:

The ornamental design for a cigarette case, substantially as shown.

CHARLES M. PRITZKER.
